The ornamental design for an automatic leveling laser marking instrument, as shown and described.

Jun. 19, 2007 (JP) 2007-016308

DESCRIPTION

(51) **LOC (8) Cl.** **10-04**

FIG. 1 is a front, top and left side perspective view of an automatic leveling laser marking instrument, showing our new design;

(52) **U.S. Cl.** **D10/66; D10/69**

FIG. 2 is a rear, top and right side perspective view thereof;

(58) **Field of Classification Search** D10/66,

FIG. 3 is a front elevational view thereof;

D10/69; 33/276, 277, 281, 285, 286, 290,

FIG. 4 is a rear elevational view thereof;

33/291-299, DIG. 21; 340/539, 825.36,

FIG. 5 is a top plan view thereof;

340/825.46, 825.49; 356/5.15, 4.01, 5.01,

FIG. 6 is a bottom plan view thereof;

356/4.05, 5.05-5.09, 5.12, 28.5, 345, 375,

FIG. 7 is a left side elevational view thereof; and,

356/3.01, 128-155, 399-400; 385/83, 97-99,

FIG. 8 is a right side elevational view thereof.

385/134-139; 701/211-213, 150, 158; 264/1.24-1.25
